UNITED STATES PATENT OFFICE.

LLOYD W. OBENCHAIN AND DURWARD B. DE LONG, OF DENVER, COLORADO.

SANITARY BERRY-BOX.

1,160,990.

Specification of Letters Patent.

Patented Nov. 16, 1915.

Application filed November 19, 1914, Serial No. 873,001. Renewed October 18, 1915. Serial No. 56,609.

To all whom it may concern:

Be it known that we, LLOYD W. OBENCHAIN and DURWARD B. DE LONG, citizens of the United States, residing at Denver, in the county of Denver and State of Colorado, have invented new and useful Improvements in Sanitary Berry-Boxes, of which the following is a specification.

This invention relates to improvements in boxes or receptacles designed especially for the reception and dispensation of fruits, vegetables, etc., and particularly to a sanitary berry box made from a single piece of material and designed, after having been once used, to be discarded.

The object of the invention is to provide a box of the character stated which may be made from a single die-cut and scored blank of paraffined paper or like material, which is simple of construction and inexpensive to manufacture, and which, when formed from the folded blank, will be strong and durable and proof against collapse under all ordinary pressures and strains.

The invention consists in the features of construction, combination and arrangement of parts hereinafter more fully described and claimed, reference being had to the accompanying drawings, in which—

Figure 1 is a perspective view of a berry box constructed in accordance with our invention; Figs. 2, 3 and 4 are vertical sections through the box taken on the planes indicated, respectively, by the lines 2—2, 3—3 and 4—4 of Fig. 1; and Fig. 5 is a plan view of the blank from which the box is made.

In carrying our invention into practice, we provide a box of rectangular or oblong rectangular form made from a single blank or piece of material, preferably of paraffined paper or other waterproof and inexpensive material. The box comprises a bottom portion A with the side portions of which are connected pair of walls B, B' and C, C', the walls B and B' being arranged at two of the opposite sides of the box, and the walls C and C' at the remaining sides of the box and at right angles to the first-named walls.

Each wall B and B' comprises a body portion of less width than the side of the bottom A with which it is connected, by which the corner portions a of the blank are made to project in the form of tongues for an interlocking action with other parts, as hereinafter described. The said body portion

of each wall B and B' is indirectly connected with the adjacent side of the bottom A by a flange b, and the body portions of the walls C and C', which are also of less width than the side of the blank to which they are attached, to coöperate with the bodies of the walls B and B' for the production of the tongues a, are likewise indirectly connected with the adjacent sides of the bottom A by flanges c. The flanges b and c are adapted, in the production of the box from the blank, to be folded downward at right angles to the bottom along the weakened or scored lines b' and c', while the respective sets of walls are bent upwardly at right angles to the bottom A but parallel with the flanges b and c, so that in the completed box the bottom A will be elevated, the box being supported by standing or resting upon the doubled downwardly-bent portions formed by the side walls and flanges, by which strength and durability will be secured, adapting the box to properly stand the weight of its contents. By thus supporting the bottom of the box in an elevated position such portion of the box will be prevented from collecting dirt and moisture and the contents of the box protected to a greater degree against the access of insects from below.

The walls B and B' are provided with corner portions or flaps B² terminating along their outer side margins in bracing members or flanges B³, which flaps and flanges are adapted to be bent along the score lines b³ and b⁴, and said flaps being provided with transverse slits or apertures b⁵.

The walls C and C' are provided with flaps or corner portions C² corresponding in form and construction with the portions B² and connecting with locking flaps C³ and C⁴. The said corner flaps and locking flaps are adapted to be bent along the score line c³ and c⁴, and the flaps C² are provided with slits c⁵ similar to the slits b⁵. The locking flaps C⁴ are slotted to provide spaced tongues c⁶ arranged adjacent to their upper and lower edges, while the locking flaps C⁴ are cut away at their upper and lower edges to provide keeper or receiving notches c⁷.

The construction of the blank will be readily understood by reference to Fig. 5 without further description, and it will be evident that as in this blank all of the por-

tions of the blank lie in the same plane a large number of these blanks may be stacked together in a flat package for convenience in storage or transportation, and that a box may be quickly and conveniently formed from each blank as occasion for its use requires.

In forming a box from the blank, it will be apparent that the flanges b and c are first 10 bent downward along the score lines b' and c' , and the walls B and B' and C and C' then bent along the score lines b^2 and c^2 so as to stand upright, whereby the bottom A will be elevated and a depending rim formed 15 by the folded flanges and walls along the lines b^2 and c^2 and the lower edges of the flaps to provide a firm foundation for the box to rest upon. After the walls are bent upward, the corner portions B^2 and C^2 are 20 bent along the score lines b^3 and c^3 so as to extend diagonally across the corners of the bottom A , leaving the triangular corner portions a projecting, the flanges B^3 and flaps C^3 and C^4 being then bent along the score 25 lines b^4 and c^4 , thus bringing the flaps of the walls C and C' to lie outside of and parallel with the flaps of the walls B and B' .

After the walls have been bent and arranged in the described manner, it will be 30 seen that the corner portions C^2 of the walls C and C' will lie in contact with the outer surfaces of the corner portions B^2 of the walls B and B' and will thus reinforce and brace the same, while the flanges B^3 will 35 lap over upon the walls C and C' and give greater strength at the adjacent points of junction. The described arrangement of the flaps will bring the slits b^5 and c^5 of the corner portions B^2 and C^2 into registry for 40 the passage of the tongues a therethrough, which when bent at an angle on the outside of said corner portions will hold the lapped corner portions connected. It will be observed that like locking flaps of the walls C and C' are disposed at diametrically opposite sides of the blank, so that when the walls 45 are folded the flap C^3 of the wall C will be disposed to interlock with the flap C^4 of the wall C' at one side of the box, while, on the contrary, the flap C^3 of the wall C' will be 50 arranged to interlock with the flap C^4 of the wall C at the diametrically opposite side of the box, the tongues c^6 of the flaps C^4 being arranged to engage the notches c' of the flaps C^3 , whereby a secure locking connection 55 is effected. The box thus constructed will be double-walled at two of the sides and reinforced at the other two sides, interlocked at the double-walled sides and the walls fastened to each other and to the bottom portion 60 at the corners of the box, making a box of maximum strength and durability. Inasmuch as this box is made of paraffined paper and formed from a single blank, it is 65 obvious that a box of inexpensive construc-

tion is provided and one which is sanitary in every respect and inexpensive enough to be used once only and then thrown away. The construction described furthermore adapts the boxes to be made at a much lower cost 70 than the ordinary wooden berry boxes.

We claim as our invention:

1. A box comprising a rectangular bottom having sets of opposed side walls, said side walls being connected with the bottom by 75 portions of less width than the bottom, whereby the corner portions of the bottom form tongues, said sets of walls having flaps and lapping corner portions, said corner portions being provided with slits for the 80 passage of said tongues.

2. A box comprising a rectangular bottom, opposed sets of counterpart side walls of less width than the sides of the bottom and connected therewith by similar flanges, 85 the said flanges being turned downwardly and the walls upwardly to form a doubled bottom rim for the box around the margins of the bottom thereof, and said side walls being provided with sets of locking flaps 90 and corner portions bent diagonally across the ends of the bottom and provided with slits, said slits of the corner portions being adapted to register when the walls are disposed in box-forming position for the passage of the tongues, and interlocking means 95 upon certain of said walls for otherwise holding the walls assembled.

3. A box formed from a single piece of material and comprising a rectangular body 100 portion, walls at two of the sides of the body portion having corner portions bent diagonally across two of the corners of the box, said corner portions being formed with slits, other side walls at the sides of the box at 105 right angles to the first-named walls and provided with similar corner portions and with locking flaps, one locking flap of each wall having notches and the other tongues to engage said notches, the notched flap of one of said side walls being interlocked with the tongued flap of the other side wall outside the first-named side walls, the corner portions of said walls being arranged to 110 overlap at adjacent corners of the box and the slits therein to register, and flanges connecting the walls with the sides of the bottom and of less width than said sides and adapted to be bent along their margins so as to form a depending rim and elevate the box 115 bottom and also leave the corners of the bottom free to form tongues to pass through the slits in the lapped corner portions.

4. A box including a bottom, pairs of opposing side walls connected by counterpart 125 flanges to the side edges of the bottom, said flanges being of less length than the respective sides of the bottom, leaving the corner portions of the latter projecting to form tongues, the flanges being bent to form dou- 130

bled rim portions projecting below the bottom, and flaps upon said walls having interlocking connections and also provided with means to interlock with said tongues.

5 5. A box formed from a single piece of material and comprising a rectangular body portion, walls at two of the sides of the body portion having corner portions bent diagonally across two of the corners of the 10 box, said corner portions being formed with slots, other side walls at the sides of the box at right angles to the first named walls and provided with similar corner portions and with locking flaps, the flaps of the respective 15 walls having interlocking connections and the corner portions of said walls being arranged to overlap at adjacent corners of the box and the slits therein to register, and tongues upon the bottom wall adapted to 20 pass through the slits in the lapped corner portions.

6. A box formed from a single piece of material and comprising a rectangular body portion, pairs of opposed walls at the sides

of the body portion having corner portions 25 bent diagonally across the corners of the box, said corner portions being arranged in lapping relation and interlocking with the corners of the body portion, two of the aforesaid side walls being provided with 30 flaps overlapping each other and the adjacent other side walls and interlocking with each other.

7. A box comprising a rectangular bottom and side walls bent upward from and interlocked with the bottom and with each other, the respective side walls being connected with the respective sides of the bottom by depending counterpart flanges, forming a 40 continuous doubled rim entirely around the margins of the box.

In testimony whereof we affix our signatures in presence of two witnesses.
